Primary Examiner — Joseph Kukella*Assistant Examiner* — Lavon M. Amerson(74) *Attorney, Agent, or Firm* — The Dobrusin Law Firm, P.C.(57) **CLAIM**

The ornamental design for a vehicle rack extrusion, as shown and described.

DESCRIPTION

FIG. 1 is a perspective view of a vehicle rack extrusion in a vehicle rack showing my new design.

FIG. 2 is an additional perspective view of a vehicle rack extrusion; and,

FIG. 3 is a side elevational view of FIG. 2.

In the drawings, the broken lines depict environmental subject matter only and form no part of the claimed design.

1 Claim, 2 Drawing Sheets(56)
